United States Patent Office

Des. 213,822
Patented Apr. 15, 1969

213,822

JUG

Richard L. Weckman, Perrysburg, Ohio, assignor to
Owens-Illinois, Inc., Toledo, Ohio, a corporation
of Ohio

Filed June 25, 1968, Ser. No. 12,494

Term of patent 14 years

Int. Cl. D9—01

U.S. Cl. D9—42

FIG. 1

FIG. 2

FIG. 3

FIG. 4

FIGURE 1 is a side elevational view of a jug, showing my new design.

FIGURE 2 is an elevational view taken from the right side of FIGURE 1.

FIGURE 3 is a top plan view thereof.

FIGURE 4 is an elevational view taken from the left side of FIGURE 1.

The side opposite that seen in FIG. 1 is a mirror image of the side shown.

The characteristic features of this design reside in the portions shown in full lines.

I claim:

The ornamental design for a jug, substantially as shown and described.
